Att'n.

surface of the panels to which they are secured adhesively. Although any suitable adhesive may be employed, it is preferred to use an adhesive that bonds on contact and which remains flexible after setting. One such adhesive is commercially available under the trade name "New-Sew."

A pair of outside end panels 23 (one shown in FIG. 9) are provided, each having formed on three of its edges, a flange 24 that is adhesively secured to the related marginal areas of the outside front, bottom and back panels 12, 13 and 14 respectively, just inwardly of the foldable edge margins 21, all as best shown in FIGS. 1 and 7.

As shown in FIGS. 1 and 13, the upper free edge margin 25 of the front wall 12 is folded over inwardly and is adhesively bonded to the underlying fabric surface of wall 12. Prior to such folding, the marginal edge 25 is suitably provided with spaced perforations 26 for a purpose to be described presently. The outside end panels 23 also have their upper marginal edges 27 folded over inwardly, as shown in FIG. 7, and are adhesively secured to the fabric surface of said wall so as to present a finished top edge to the purse.

After the outside walls of the purse have been assembled as described above, the flap panel 16 is folded over along fold line 28 to lie flat against flap panel 15 and the fabric surfaces of the two are adhesively secured together. Prior to this folding and securing, a pair of strap holes 29 are cut in each panel 15, 16, and the marginal edge 30 of each hole is rolled over and adhesively bonded to the fabric surface of the material. Thus, when the panels 15, 16 are joined as aforesaid, the holes 29 in one panel register with the holes 29 in the other panel to define reinforced finished edge openings through which a strap 31, described hereinafter, is extended.

The purse liner may now be assembled. As noted hereinabove this liner is comprised of the panels 17, 18 and 19 (FIG. 2) which are joined with liner end panels 32 (FIG. 11) in a manner now to be described.

The panels 17, 18 and 19 each have their end edges formed with a series of tongues or extensions 33 having a narrow flap 34 therebetween. Each of these tongue extensions is perforated, as at 35. The liner end panel 32 has similar perforated tongue extensions 36 and flaps 37 (FIG. 11) on its side and bottom edges. Prior to assembly the narrow flaps 34 and 37 are rolled over the fabric surface of the material and are secured thereto by adhesive to present a finished edge in the spaces between tongues 33 and 36.

The end panel 32 then is positioned in register with the related end of the partially formed front, back and bottom liner walls or panels (as shown in FIG. 10) and in such manner that the tongue extensions 33 on said last named panels register with the respective spaces between tongue extensions 36 on the end panel, and the tongue extensions 36 on the end panel register with the respective spaces between the tongues 33 on the front, bottom and back liner panels. The tongues 33 and 36 then are folded over against the outside surface of the associated panel and an adhesive is applied thereto. This adhesive enters through the aperture in each tongue extension filling same and thus bonding firmly to the underlying fabric surface. Additional strength is afforded the joining by adhesively securing one or more strips 38 of fabric, preferably cut on a bias, on each tongue extension, as best illustrated in FIG. 10. The same procedure is followed in securing the other liner end wall 32 in place. The resulting liner assembly may now be pushed down into the outside purse structure for lining the same. However, before doing this the hand strap 31 and a latch 39 (FIG. 17) are mounted and the lining is fitted with one or more pocket assemblies 41 which also are fabricated from

the same type of plastic coated fabric as the purse body and lining.

One such pocket assembly 41 is best illustrated in FIGS. 13, 14 wherein it will be seen that the pocket assembly is fabricated by folding a single piece of such material with the plastic surface outwardly so as to provide a mounting wall 42, a rear pocket wall 43, a front pocket wall 44 and a facing 45. The facing has its bottom margin 46 folded upwardly inwardly and secured adhesively to the fabric surface of the material as shown. The mounting wall 42 and the underlying area of the liner wall are coincidentally slit as at 47 (FIG. 15) and two strips 48 of linen or the like are threaded into the slits and their edges are folded over in opposite directions to overlie the outside fabric faces of the pocket mounting wall 42 and the liner wall 19 and are adhesively secured thereto all as shown in FIGS. 13-15. The ends of the pocket facing 45 and front pocket wall 44 are tucked beneath the back wall 43 and adhesively secured as shown in FIG. 16.

The hasp or latch 39 may be of any suitable type but it is preferred to use one having a base 49 from which a stem 51 extends and which stem is projected through a hole in the outside front wall 12. Preferably the base 49 has a pair of openings therein through which a strip of fabric 52 may be extended and which strip is adhesively bonded to the fabric face of the outside front wall. This form of mounting avoids the need for machine applying the latch and further makes it less difficult to replace should such replacement become necessary or desirable.

As noted hereinabove, the hand strap 31 is partially secured in place before the liner assembly is positioned and secured. Referring now to FIGS. 3 to 6, the strap 31 is comprised of a strip of plastic coated fabric material like that of the purse body and lining. The strap blank is relatively wide in its medial portion 53 and is formed on both longitudinal edges with a series of mutually spaced holes 54. Its end portions 55 are of lesser width and are of a length responding to the height of the purse end walls 23. Its extreme end or terminal portions 56 are of still lesser width.

Prior to folding and forming the strip into a strap, a pair of chains 57 are laid along the margins thereof. These chains are of greater length than the length of the strip so as to extend beyond each end, as at 57a. An adhesive is applied to the fabric surface of the strip (face up in FIG. 3) and the margins 55a of end portions 55 are rolled over the chains and adhesively secured, as best shown in FIG. 4. The margin 58 of the intermediate portion then is folded over the related chain 57. The other margin 59 is folded over upon itself, as at 59a, and then it is folded inwardly as shown to overlie the margin 58. This folding is carefully attended to so as to insure that the perforations 54 in the margins register one with the other. When this is accomplished, a tool, such as the end of a pencil, is used to press the folded margin 59 down into the holes (FIG. 5) so as to carry its fabric face into bonding contact with the fabric face of the underlying main body of the strip. The result is tight bonding of the folded assembly and the creation of ornamental detents 61 on the surface of the finished strap. Preferably, the chains are wrapped with twine or the like, as at 62 (FIG. 6) to negative any chemical reaction between the metal of the chains and the adhesive used.

The strap may now be inserted into the assembly by initially extending its ends through the strap holes 29 in the flap 15-16. The free terminal ends are secured in like fashion to the body and liner consequently only one end attachment will be described. Specifically, a pair of holes 63 (FIG. 8) is provided in the outside bottom wall 13 of the purse closely adjacent to end wall 23 and the two chain ends 57a are threaded downwardly one through each of these holes and then crossed over on the outside of the bottom wall and are then carried upwardly through

the other of said holes and tied, as at 64, securely inside the purse. A stiffener sheet 65 (FIG. 7) of any light weight material then is placed in the bottom of the purse and the liner is then press fitted into place. During this operation the liner walls are coated with adhesive and the liner end walls 32 are pressed firmly against the fabric face of the strap intermediate portions 55 to adhesively bond them to the liner end walls. The terminal flap 56 of the strap is similarly bonded adhesively to the bottom face of the liner bottom wall.

Although I have described a preferred embodiment of my invention in considerable detail, it will be understood that the description thereof is intended to be illustrative, rather than restrictive, as many details of the structure disclosed may be modified or changed and the steps of the method may be varied, without departing from the spirit or scope of the invention. Accordingly, I do not desire to be restricted to the exact construction, method and means described.

I claim:

1. An article of the character described comprising a blank of fabric material faced on one surface with a plastic coating, said blank being foldable to provide outside front, back and bottom walls, separate blanks secured to said walls to provide end walls, an integral liner formed by folding said blank to define front, back and bottom liner walls, separate blanks forming end walls of said liner, said liner front, back and bottom walls and end walls having their fabric surfaces disposed outwardly, and each being formed on related edges with tongue extensions that overlie the related wall and are secured thereto by an adhesive.

2. The article recited in claim 1, in which the tongue extensions are perforated to allow the adhesive to penetrate to the fabric faces of the attached walls.

3. The article recited in claim 1, in which reinforcing strips overlie and are bonded to each tongue extension and to the related area of the wall to which said tongue extension is secured.

4. In a purse or like product, a liner comprising front, back, bottom and end panels, said front, back and bottom panels being integral one with the other, a plurality of tongue extensions formed on the end edges of said front, back and bottom panels and defining spaces between said tongue extensions, a plurality of tongue extensions formed on three edges of the end panels and defining spaces between the tongue extensions, the tongue extensions on the front, back and bottom panels registering with the spaces on the end panels and the tongue extensions on the end panels registering with the spaces on the front, back and bottom panels, said tongue extensions being foldable to overlie the outside surface of the related panels, and an adhesive bonding said tongue extensions to said underlying panels.

5. In the purse recited in claim 4, in which strips of fabric overlie the tongue extensions and adjacent areas of the underlying panels and are adhesively bonded thereto.
